BENJAMIN SKIDMORE, JR., OF CHICAGO, ILLINOIS.

HYDRAULIC AIR-COMPRESSOR AND VACUUM PRODUCER.

1,392,857.

Specification of Letters Patent.

Patented Oct. 4, 1921.

Application filed August 12, 1918. Serial No. 249,755.

To all whom it may concern:

Be it known that I, BENJAMIN SKIDMORE, Jr., a citizen of the United States, residing at Chicago, in the county of Cook and State 5 of Illinois, have invented certain new and useful Improvements in Hydraulic Air-Compressors and Vacuum-Producers, of which the following is a specification.

This invention relates to improvements 10 in hydraulic air compressors and vacuum producers and has for its object to provide improved means for removing a portion of liquid from a body or supply of liquid, and which means also operates to deliver air or 15 a gaseous fluid into the said body or supply to replace the liquid removed therefrom. In my applications Serial Nos. 216618 and 249500 I have disclosed an apparatus of this type in which the liquid and fluid transferring means is operated by the direct action 20 of the fluid thereon, but in the present application the liquid and fluid transferring means is actuated by mechanism provided for that purpose.

25 A further object of the present invention is to provide an improved apparatus of this character embodying a vacuum chamber and a compression chamber, and means whereby liquid may be readily transferred 30 from one of the chambers into the other chamber for creating a partial vacuum in one of the chambers or a compression in the other chamber by maintaining substantially constant liquid levels in the chambers.

35 To the attainment of these ends and the accomplishment of other new and useful objects as will appear the invention consists in the features of novelty in substantially the construction, combination and arrangement 40 of the several parts, hereinafter more fully described and claimed and shown in the accompanying drawings illustrating this invention and in which:

Figure 1 is a vertical longitudinal sectional view of an improved apparatus of this character constructed in accordance with the principles of this invention.

Fig. 2 is a vertical sectional view taken on line 2—2 Fig. 1.

50 Fig. 3 is a detail sectional view of a modified form of the invention.

Fig. 4 is a view similar to Fig. 1 of another form of the invention.

55 Fig. 5 is a vertical sectional view taken on line 5—5, Fig. 4.

Referring more particularly to the draw-

ings and the form of the invention shown in Figs. 1 and 2, there is shown an apparatus embodying two chambers or reservoirs 10—11, preferably superposed, and arranged intermediate these reservoirs is a rotatable element 12 which is preferably cylindrical in cross section and is hollow, having an entrance opening 13, the edges 14 of which are reduced or beveled as shown to 60 permit the edges to pass freely through the water when the element is rotated. The element is rotatable about an axle 15 which is journaled in suitable bearings 16, and motion is imparted thereto from a motor 17 65 through a suitable drive connection 18.

This element is adapted to rotate within a suitable casing or housing 19 formed in any suitable manner so as to encompass the periphery of the element, and the housing 75 is provided with an opening 21 having communication with the reservoir 10, and a similar opening 22 having communication with the reservoir 11, so that the only source of communication between the reservoirs 10 80 and 11 is through the housing or casing 19, and this communicating passage is controlled by the rotatable element 12 which is adapted, when in the position shown in Fig. 1, to receive the liquid from the reservoir 10, 85 and when rotated, will, when the opening 13 registers with the opening 22, discharge the liquid into the reservoir 11. After the liquid has been discharged from the element 12, the element will be filled with a gaseous 90 fluid or vapor from the reservoir 11, so that when the element 12 is rotated further, so as to bring the opening 13 into communication with the opening 21, the gaseous fluid or vapor will be delivered into the reservoir 95 10 through the liquid therein. This operation will create a suction or partial vacuum in the reservoir 11, which will be manifested in the pipe or conduit 23, and if desired, a controlling valve 24 may be provided 100 in the passage 23. The gaseous fluid or vapor which is withdrawn from the reservoir 11 and delivered into the reservoir 10, may be discharged from the latter through a pipe 25 to any suitable point, and a valve 105 26 may be provided in this pipe so that when the same is closed, the gaseous fluid or vapor delivered into the reservoir 10 will be compressed therein. The compression is effected, preferably by maintaining the 110 liquid in the reservoir 10 at a substantially constant level, which may be accomplished

in any suitable manner, such as by means of a centrifugal pump 27 which receives its supply of liquid through the pipe 28 which has communication with the reservoir 11 and discharges the liquid withdrawn from the reservoir 11 through a pipe 29 back into the reservoir 10.

Thus, it will be seen that as the liquid is removed from the reservoir 10, it will be transferred back into the reservoir 10 from the reservoir 11.

In the form of the invention shown in Fig. 3, the rotatable element 30 is preferably in the form of a solid cylindrical element having diametrically opposite portions 31-32 removed therefrom to form pockets so as to increase the rapidity of action of the apparatus.

In the form of the invention shown in Figs. 4 and 5, the rotatable element 33 is shown as being elliptical or oval in cross section, the walls of the casing or housing 19 being so arranged that when the element is in the position shown in Fig. 4, the ends thereof will be in close proximity to the wall of the casing or housing 19 to prevent the liquid from flowing between the element and the casing wall, and the flat or elongated portions 34 of the element will stand opposite the openings 21-22 in the casing or housing. As the element 33 is rotated in the direction of the arrow, it will be manifest that the portions 34 of the element will cooperate with the walls of the casing or housing 19 to form pockets, one of the pockets receiving liquid from the reservoir 10, while the other pocket receives the gaseous fluid or vapor from the reservoir 11. The liquid will be conveyed by the element 33 to be discharged into the reservoir 11 through the opening 22, and the gaseous fluid or vapor will be conveyed by the other pocket from the reservoir 11 to be discharged into the reservoir 10.

In order to strip or remove the gaseous fluid or vapor from the element 33 which would be confined closely to the periphery thereof, any suitable means may be provided, but preferably a means whereby the liquid itself may be employed as a stripper directed against the element. This may be accomplished in any suitable manner, such as by means of a nozzle 35 of a desired and proper configuration which is supported adjacent the element 33 with its outlet directed against the periphery thereof. The nozzle is preferably supported by means of a pipe 36 which has communication with the centrifugal pump 27, the latter being operated by means of the motor 17 in a manner similar to the manner shown in Fig. 2.

It is thought that the operation of this apparatus will be clearly understood from the foregoing specification, and with this improved apparatus, it will be manifest that

the liquid will be intermittently removed in predetermined quantities from the reservoir 10 and delivered into the reservoir 11, at the same time a predetermined quantity of gaseous fluid or vapor will be removed from the reservoir 11 and discharged or delivered into the reservoir 10 to replace the liquid removed therefrom, with the result that a suction or partial vacuum will be created in the reservoir 11, and a compression may be obtained in the reservoir 10 by closing the valve 26. At the same time the liquid is maintained at a substantially constant level in the reservoir 10 by transferring the liquid back into the reservoir 10 from the reservoir 11.

What is claimed as new is:

1. An apparatus of the character described embodying a rotatable element, a reservoir for impounding a desired quantity of water at a desired elevation above said element, said element operating to control the discharge of water from the said reservoir; a reservoir for receiving water discharged by said element, said element being shaped to withdraw fluid or vapor from the second recited reservoir and deliver the same into the first recited reservoir, and power mechanism connected with the said element for rotating it.

2. An apparatus of the character described embodying a rotatable element, a reservoir for impounding a desired quantity of water at a desired elevation above said element, said element operating to control the discharge of water from the said reservoir, a reservoir for receiving water discharged by said element, said element being shaped to withdraw fluid or vapor from the second recited reservoir and deliver the same into the first recited reservoir, and through the liquid in the latter to be compressed, and power mechanism connected with the said element for rotating it.

3. An apparatus of the character described, embodying a rotatable element, a reservoir for impounding a desired quantity of water at a desired elevation above said element, said element operating to control the discharge of water from the said reservoir, a reservoir for receiving water discharged by said element, said element being shaped to withdraw fluid or vapor from the second recited reservoir and deliver the same into the first recited reservoir, power mechanism connected with the said element for rotating it, and means for maintaining the liquid in the first recited reservoir at a substantially constant level.

4. An apparatus of the character described, embodying a rotary element, a reservoir for impounding a desired quantity of water at a desired elevation above said element to be delivered to the element, power mechanism connected with the said element

for rotating it, a reservoir for receiving water discharged by said element, said element being shaped to withdraw fluid or vapor from the second recited reservoir and deliver 5 the same into the first recited reservoir, and provisions for maintaining the liquid in the respective reservoirs at substantially constant levels, the said provisions embodying means other than the said element for transferring the liquid from one of the reservoirs into the other reservoir.

5. An apparatus of the character described, embodying a rotatable element, a reservoir for impounding a desired quantity 15 of water above said element, a reservoir for receiving the water discharged by the element, a casing in which the said element is housed, said casing having openings forming communications with the respective reservoirs whereby water will be delivered 20 through the casing from one reservoir to the other by the rotation of the element and whereby fluid or vapor will be withdrawn from the second recited reservoir and delivered 25 into the first said reservoir, and power mechanism connected with the element for rotating it, the said element having portions thereof so shaped as to coöperate with the wall of the casing to trap 30 predetermined quantities of water, and vapor and fluid being withdrawn from their respective reservoirs to be delivered to the other reservoir.

6. An apparatus of the character described, embodying a rotatable element, a reservoir for impounding a desired quantity 35 of water above said element, a reservoir for receiving the water discharged by the element, a casing in which the said element is housed, said casing having openings forming communications with the respective reservoirs whereby water will be delivered 45 through the casing from one reservoir to the other by the rotation of the element and whereby fluid or vapor will be withdrawn from the second recited reservoir and delivered 50 into the first said reservoir, and power mechanism connected with the element having a portion shaped to form a pocket opening through the periphery thereof and which pocket is adapted to be closed by the casing wall.

7. An apparatus of the character described, embodying a rotatable element, a reservoir for impounding a desired quantity 55 of water above said element, a reservoir for receiving the water discharged by the element, a casing in which the said element is housed, said casing having openings forming communications with the respective reservoirs whereby water will be delivered 60 through the casing from one reservoir to the other by the rotation of the element and whereby fluid or vapor will be withdrawn

from the second recited reservoir and delivered into the first said reservoir, and power mechanism connected with the element for rotating it, the said element being of a hollow construction having an opening 70 through its periphery.

8. An apparatus of the character described, embodying a rotatable element, a reservoir for impounding a desired quantity of water above said element, a reservoir for 75 receiving the water discharged by the element, a casing in which the said element is housed, said casing having openings forming communications with the respective reservoirs whereby water will be delivered 80 through the casing from one reservoir to the other by the rotation of the element, and whereby fluid or vapor will be withdrawn from the second recited reservoir and delivered into the first said reservoir, and power mechanism connected with the element for 85 rotating it, the walls of the casing standing in close proximity to the periphery of the said element, and operating to trap the liquid and the fluid or vapor as they 90 pass through the casing.

9. An apparatus of the character described embodying a rotatable element, a reservoir for impounding a desired quantity of water at a desired elevation above the element, a housing in which the element rotates, said housing having an opening communicating with the reservoir, and a discharge outlet, said housing being substantially cylindrical in cross section, the walls 95 of the housing standing in close proximity to the periphery of the element, and power mechanism connected with the element for rotating it in the housing, said element being of a construction to coöperate with the housing walls to convey the water through the housing and trap predetermined quantities of the water during its passage through the housing, the said element also operating to trap and convey a similar predetermined 100 quantity of fluid or vapor and deliver the same into the reservoir.

10. An apparatus of the character described embodying a rotatable element, a reservoir for impounding a desired quantity 115 of water at a desired elevation above the element, a housing in which the element rotates, said housing having an opening communicating with the reservoir, and a discharge outlet, said housing being substantially cylindrical in cross section, the walls of the housing standing in close proximity to the periphery of the element, and power mechanism connected with the element for rotating it in the housing, said element being hollow 120 and having an opening serving as an inlet and an outlet for the liquid, whereby the water will be conveyed through the housing and the casing wall will serve to close said opening, said element also operating to re- 125 130

ceive fluid or vapor after the water has been discharged therefrom and deliver the same into the reservoir through the liquid therein

11. An apparatus of the character described embodying a rotatable element, a reservoir for impounding a desired quantity of water at a desired elevation above the element, a housing in which the element rotates, said housing having an opening 10 communicating with the reservoir, and a discharge outlet, said housing being substantially cylindrical in cross section, the walls of the housing standing in close proximity to the periphery of the element, and power

mechanism connected with the element for 15 rotating it in the housing, said element being shaped to form an open pocket whereby the water will be conveyed through the housing and the casing wall will serve to close said opening, said element also operating to receive fluid or vapor after the water has been discharged therefrom and deliver the same into the reservoir through the liquid therein.

In testimony whereof I have signed my 25 name to this specification, on this 8th day of August, A. D. 1918.

BENJAMIN SKIDMORE, JR.
